UNITED STATES PATENT OFFICE

2,574,871

RESILIENT CUSHIONING SUPPORT FOR
CHAIRS OR THE LIKE

Maximilian Heller, London, England

Application October 7, 1947; Serial No. 778,519
In Great Britain October 24, 1946

4 Claims. (Cl. 155—179)

1
The present invention relates to a cushioning support for chairs, settees, divans, bed-insets, vehicle seats or the like (hereinafter referred to as "chair or the like") and has for its object the provision of a reliable, simple and exceptionally resilient structure.

According to the invention there is provided a resilient cushioning support for chairs or the like comprising in combination a rigid support frame wherein an essentially centrally positioned member made of inextensible material is held suspended solely by a number of oppositely arranged tensioned tensile springs extending directly from the central member to the four corners of a rectangular area on said frame, there being at least two such springs at each said corner radiating divergently therefrom towards the central member, the whole construction being such that said cushion support constituted by the central member and suspension springs extends across a comparatively large surface area without being linked to the intermediate portions of said support frame and provides its greatest degree of resilient support at and around the central member.

The structure in accordance with this present invention allows of attachment in an elevated position relative to the substructure of a frame and also enables the formation of raised sprung edges.

The invention further comprises various other features and forms of constructions which will appear from the following description made with reference to the accompanying drawing which illustrates the invention by way of example and in which:

Fig. 1 shows diagrammatically a cushioning support in accordance with this invention.

Fig. 2 is a modification of Fig. 1.

Fig. 3 is a perspective view of an armchair, and

Fig. 4 illustrates three adjoining cushioning supports.

Referring to the drawings, Fig. 1 shows a cushioning support for a seat or back of a chair or the like in which a comparatively small and centrally positioned member *a* is held suspended by means of oppositely arranged and tensioned bearer springs *b* the latter forming V-shaped structures the digressing end portions of said structure being secured to said member *a* whilst the apices of said V structures are anchored at hooks *c*, eyes, studs or like attachment fixtures provided at the four corners of the frame. The frame is rigid or substantially rigid and may be as shown in Figure 3, being shaped so that the

anchorage parts to which the attachment fixtures *c* are secured are located at the corners of a substantially rectangular area across which the cushioning support extends.

5 Each of the individual bearer springs *b* is by way of example composed of a plurality of component springs linked together end to end or connected by means of intermediary rings, eyes, discs or like links *d* and the joints of said component springs are employed for engaging and holding in position panel-filling elements *e* consisting of ropes, chains, tensile springs, bands or the like. The elements *e* may be attached at said links *d* or may pass through the latter so as to form zig-zag, or like designs, or said elements *e* may be arranged in a spider-web-like manner as by way of example illustrated in this figure.

The member *a* may consist of plates, rings, sheets or the like and may be composed of wood, metal, plastic compositions, inextensible fabric or like material.

10 Fig. 2 is a modification of Fig. 1 in which the bearer springs *b* extend in a continuous stretch. Between the opposing attachment-fixtures *c* are strung terminal springs *f* to form resilient edges and one or more of the latter may be provided with elements *g* consisting of springs or of any suitable flexible or elastic material, said elements *g* serving for sub-dividing the open spaces between the terminal springs *f* and member *a*. The bearer springs *b* extend in an essentially diagonal direction following the most efficient course of the "pull" exerted by said bearer springs *b* at the member *a* when the cushioning support is occupied.

15 To prevent overcrowding and overstraining of the fixtures *c* by securing a number of springs to a single one of said fixtures, each of the four anchorage parts of the frame may be provided with a plurality of attachment-fixtures *c*, the frame being, for example, as shown in Figure 3 with the anchorage parts at the corners of a substantially rectangular area across which the cushioning support extends.

20 In order to still further increase the comfort, the springs employed in one unit may differ from each other relative to their strength, diameter or tension e. g. springs *b* may be made of a heavier gauge and may be more tensioned when mounted than springs *f*, or the latter forming the seat-front edge of a chair may be more powerful than the spring or springs *f* constituting the rear edge of the same seat. In this manner the elastic resistance of units in accordance with this inven-

tion may be regulated and adjusted according to requirements.

The arm-chair shown in Fig. 3 illustrates the mode of raising the cushioning support above the sub-structure of a rigid or substantially rigid tubular frame so as to extend freely over a substantially rectangular seat or back area. Each of the two sets shown is secured only to four anchorage parts of the frame by means of attachment fixtures *c* and forms a coherent unit which is capable of a highly resilient performance when occupied.

The comfort attained by the cushioning support in accordance with this invention is infinitely greater than with tension spring arrangements in which the springs are anchored to the interior portions of the side members of frames since in the latter case the anchorages of the springs hamper the elastic movement of the support on occupation.

Fig. 4 illustrates an assembly comprising three adjoining cushioning supports in accordance with the present invention. Each support extends over a substantially rectangular area and is secured through attachment fixtures *c* to a rigid or substantially rigid frame having pillars to which the fixtures *c* can be secured as in Figure 3. The terminal springs *f* are shown to be composed of a number of component springs having intermediate their ends strips *h* or the like, the latter extending over the width and length of the entire surface of said adjoining cushioning supports. In order to reduce open spaces in this structure resilient or flexible strips *i* are employed the opposing ends of said strips *i* being provided with tension springs *j* the latter being secured to the fixtures *c*. The strips *h* may be of metal, plywood, plastic, or the like, which materials and also webbing are suitable for the strips *i*.

I claim:

1. A resilient cushion support for a chair or the like extending across a substantially rectangular area within a rigid frame, comprising a plurality of tensile springs, a substantially centrally positioned member solely suspended by said tensile springs the latter being oppositely tensioned when mounted, said substantially centrally positioned member being made of inextensible material and at least two of said springs extending directly and convergently from said central member to each corner of said rectangular area, the whole construction being such that said cushion support constituted by said central member and said suspension springs extends across a comparatively large area and provides its greatest degree of resilient support at and around the central member.

2. A resilient cushion support for a chair or the like extending across a substantially rectangular area within a rigid frame, comprising a plurality of tensile springs, a substantially cen-

trally positioned member solely suspended by said tensile springs the latter being oppositely tensioned when mounted, said substantially centrally positioned member being made of inextensible material and at least two of said springs extending directly and convergently from said central member to each corner of said rectangular area, at least one of the ends of said cushion support having a tensioned marginal tensile spring having its opposing ends secured at two of said corners, said marginal spring forming a freely oscillating edge, at least one flexible element extending between and interconnecting said marginal spring and said central member, the whole construction being such that said cushion support constituted by said central member, said suspension springs, said marginal spring and said flexible element form a coherent unit extending across a comparatively large area and provides its greatest degree of resilient support at and around the central member.

3. A plurality of resilient cushion supports as claimed in claim 2, said supports adjoining each other and forming a unitary supporting surface.

4. In an article of furniture the combination comprising a substantially rigid frame, attachment fixtures secured to said frame at the corners of a substantially rectangular area within said frame, a plurality of main tensile springs each having an end secured to one of said attachment fixtures, a substantially centrally positioned member maintained in position by said main tensile springs, each of said main tensile springs having an end secured to said members, said main tensile springs being under tension when mounted and at least two of said main tensile springs extending convergently from said member to each of said attachment fixtures, the arrangement being such that said springs and said member form a coherent cushion support extending across said rectangular area and providing very effective and resilient support at and around said central member.
